UNITED STATES PATENT OFFICE.

DAVID F. HEVERLY, OF ROGERS, ARKANSAS,

SCYTHE-SNATH FASTENER.

1,236,710.

Specification of Letters Patent. Patented Aug. 14, 1917.

Application filed January 16, 1914, Serial No. 812,567.

To all whom it may concern:

Be it known that I, DAVID F. HEVERLY, citizen of the United States, residing at Rogers, in the county of Benton and State of Arkansas, have invented certain new and useful Improvements in Scythe-Snath Fasteners, of which the following is a specification.

This invention relates to an improved scythe-snath fastener, and the primary object thereof is to provide a device which is not only extremely simple in construction, but is also efficient and useful in operation, and can be manufactured and placed upon the market at a minimum cost.

A further object of the invention resides in the provision of means whereby scythe blades having shanks or tangs varying in size, may be readily and easily fastened to the snath; such fastening being effected in a novel and peculiar manner, the nature of which is such as to permit quick adjustment of the blades to various angles with respect to the snath or handle.

The invention further contemplates the provision of an attaching plate having means associated therewith whereby the blade shanks may be readily clamped and unclamped relative thereto.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings, wherein like characters denote like or corresponding parts throughout the several views, and in which:

Figure 1 is a side elevation illustrating the improved scythe-snath fastener;

Fig. 2 is a similar view, the opposite side to that illustrated in Fig. 1 being shown;

Fig. 3 is an enlarged section on the line 3—3 of Fig. 1;

Fig. 4 is a similar view on the line 4—4 of Fig. 2; and

Fig. 5 is a similar view on the line 5—5 of Fig. 2.

Referring now to the drawings by numeral, 1 designates the snath and 2 the blade, the latter having the usual angular shank or

extension 3, formed integrally therewith and at one end thereof. The free end of the shank is provided with an integrally formed locking tongue 4, which, in the present instance, is disposed for engagement with the under face of an attaching plate 5, the latter being provided with openings 6, through any one of which the said tongue 4 extends.

The attaching plate 5 is permanently or fixedly secured to the snath 1 through the medium of screws 6', the said snath being cut away as at 7 to provide a flat securing surface for the said plate.

The opposite side of the snath 1 is likewise cut away as at 8 to provide a securing surface for a suitable wedge block 9 which, when forced into firm engagement with the said flat securing surface, is locked or fastened by means of screws 10 extending into the body of the said snath 1.

To maintain the tongue 4 within the openings 6, and to lock the shank 3 immovable with respect to the attaching plate 5, I provide a securing ring 11, enlarged as at 12, whereby the formation of a seat 13 for the shank 3 is made possible. The said ring 11, at a point diametrically opposite to the enlargement 12, is again enlarged as at 14, the said enlargement having a peripheral recess 15 formed therein for the reception of the head of a set-nut or bolt 16, the shank of which is adapted for engagement with the wedge block 9 as is clearly illustrated in Fig. 3 of the drawings.

Beneath each opening 6 of the attaching plate, a recess 17 is formed, within which the locking tongue 4 of the shank is fitted when disposed to extend into any one of the said openings 6.

To effect angular adjustment of the blade 2, the nut 16 is operated to withdraw the said screw from engagement with the wedge block 9; the screws 10 are removed, and the wedge block forced from beneath the securing ring 11, whereupon a sliding movement 100 of the ring upon the snath 1 may be accomplished. By sliding the ring until without engagement with the shank 3, it is apparent that the free end of the latter, or the locking tongue 4, may be withdrawn from the opening 6, and the blade 2 removed. The insertion of the locking tongue 4 within another of the openings 6, and the arrangement of the ring 11 and the block 9 in the manner above described, will lock the blade 2 im-

movable with respect to the snath 1 and at an angle varying in degree to the angle assumed before adjustment.

From the above, taken in connection with the accompanying drawings, it will be noted that the openings 6 are formed by forcing one of the plates inwardly, the said tongues serving in the capacity of retaining elements whereby the said plates are locked against lateral as well as longitudinal movement independent of the snath; that the engagement between the walls of the recess 13 and the shank 3 prevent lateral movement of the latter; and that by enlarging the securing ring 11 as at 12, the formation of the recess 13 will in no way weaken the said ring at this particular point. In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes, in details of construction, proportion and arrangement of parts may be resorted to, when required, without sacrificing any of the advantages of my invention, as defined in the appended claims.

Having thus fully described my invention, what I claim as new and desire to secure by Letters Patent, is:

1. A device for fastening the shank of the blade to the scythe-snath including an attaching plate secured to the snath, said plate having a plurality of openings formed therein, said openings being disposed in registration with recesses of said snath, a

locking tongue formed upon the extremity of said shank, said tongue being seated within one of said recesses and disposed to extend through one of said plate openings, a circular clamping band slidable upon said snath, said band having a recessed enlargement formed on its inner face, said last mentioned recess being disposed to receive said shank and clamp it between the wall of the recess and said attaching plate, a wedge member engageable between said band and secured to said snath, and means adjustable upon said band and engageable with said wedge member to lock the said band immovable with respect to said shank, as and for the purpose set forth: 55

2. In a scythe, a snath formed at one end with a pair of parallel flat surfaces, one of said surfaces being provided with tongue receiving recesses, a snath plate secured to said recessed surface and having apertures registering with the recesses, a circular clamping band slidable upon said snath, internal and external recessed enlargements formed on opposite sides of said band, a scythe blade accommodated in the recess of the internal enlargement and lying against one of the flat surfaces of the snath, a wedge block engageable in said band and with the other flat surface of said snath and secured to said snath, and means adjustable through 70 said last mentioned enlargement to clamp said band to said wedge block. 65

In testimony whereof I affix my signature in presence of two witnesses.

DAVID F. HEVERLY.
